UNITED STATES PATENT OFFICE.

WILLIAM O. CAMPBELL, OF ST. LOUIS, MISSOURI.

SMOKING-PIPE.

No. 900,482.

Specification of Letters Patent.

Patented Oct. 6, 1908.

Application filed January 6, 1908. Serial No. 409,472.

To all whom it may concern:

Be it known that I, WILLIAM O. CAMPBELL, citizen of the United States, residing at St. Louis, State of Missouri, have invented certain new and useful Improvements in Smoking-Pipes, of which the following is a full, clear, and exact description, reference being had to the accompanying drawings, forming a part hereof.

10 My invention has relation to improvements in smoking-pipes; and it consists in the novel construction of pipe more fully set forth in the specification and pointed out in the claim.

15 In the drawings, Figure 1 is a side elevation of my pipe with parts broken away; and Fig. 2 is a perspective of a portion of the plug confined within the stem.

The object of my invention is to construct 20 a smoking pipe which provides means for compelling the smoke to travel in a spiral or equivalent path on its way from the bowl to the mouth-piece, the total length of such a path being far in excess of the length of the 25 stem and mouth-piece combined, so that when the smoke passes out of the mouth-piece into the mouth of the smoker, it will have become sufficiently cooled by reason of such increased length of travel, as not to 30 burn the tongue or other portions of the smoker's mouth.

The advantages of the construction will be better apparent from a detailed description of the invention which is as follows:

35 Referring to the drawings, B, represents a conventional pipe-bowl, S, the stem, M, the mouth-piece, and F, a metal ferrule carrying the mouth-piece, the ferrule itself being passed over the adjacent end of the stem.

40 The parts described are well understood and do not in themselves constitute any part of my present invention.

Adapted to be inserted into the stem S, and 45 extending preferably the entire length of the same, is a plug P, which may be removed at any time for purposes of cleaning. This plug

is provided with a spiral peripheral groove a; and since the outer wall of the plug snugly fits the inner wall of the stem, the groove a thereby forms a spiral passage-way the total length of which materially exceeds the length of the stem. In this way, the smoke from the bowl by reason of its increased distance of travel is materially cooled by the time it enters the passage-way of the mouth-piece, and the burning effect so usually experienced in smoking a pipe disappears. The end of the plug adjacent the inner hollow nipple n of the mouth-piece is beveled as shown at b, the edge of the bevel passing between the tapering walls of the nipple and the stem S, this arrangement permitting an unobstructed passage of the smoke into the mouth-piece. While the extended path for the smoke is preferably a spiral one as shown, any other elongated path may be substituted therefor, although the spiral form is preferable, permitting as it does, the ready cleaning of the parts.

Having described my invention, what I claim is:

A smoking-pipe comprising a bowl, an open-ended hollow stem carried by the same, a mouth-piece at the outer end of the stem, a nipple formed at the inner end of the passage of the mouth-piece and having inner tapering walls, a plug within the stem and engaging the inner walls of the stem, the said plug having a peripheral spiral formation forming a circuitous passage for the smoke, the end of the plug adjacent the nipple beveling sufficiently to pass between the tapering walls of the nipple and stem, and permit the smoke discharged from the passage to enter the nipple and the passage of the mouth-piece, substantially as set forth.

In testimony whereof I affix my signature in presence of two witnesses.

WILLIAM O. CAMPBELL.
